UNITED STATES PATENT OFFICE

THEODORE W. RIEKE, OF AUBURN, INDIANA, ASSIGNOR TO RIEKE METAL PRODUCTS CORPORATION, OF AUBURN, INDIANA, A CORPORATION OF INDIANA

BARREL

Application filed July 16, 1927. Serial No 206,220.

The present invention relates to containers or barrels, and more particularly to an improved bung ring and seal therefor.

One object of the invention is to provide a bung ring which may be secured in fixed and sealed relation upon one side of one wall of a barrel and form a support for a plug when screwed into the ring and which at the same time affords means for completely 10 draining the barrel when inverted.

Another object of the invention is to provide an improved seal which may be so related with the plug that any unauthorized opening or tampering with the plug will be 15 readily indicated.

Other objects of the invention will be apparent to those skilled in the art to which my invention relates from the following description taken in connection with the accompanying drawings, wherein

Figure 1 is a fragmentary plan view of one wall of a barrel showing the up-set wall ready to receive a bung ring.

Figure 2 is a section on the line 2—2 of 25 Figure 1.

Figure 3 is a detail top plan view of a bung ring constructed according to this invention.

Figure 4 is a section taken through the 30 same.

Figure 5 is a transverse section, enlarged, through the ring and barrel wall.

Figure 6 is a view similar to Figure 5 with the plug in position and showing in dotted 35 lines one form of sealing cap.

Figure 7 is a view similar to Figure 6, but showing the sealing cap in section and plug in elevation.

Figure 8 is a top plan view of the parts 40 shown in Figure 7.

Figure 9 is a side elevation, partly broken away, showing a modified form of sealing cap, and

Figure 10 is a top plan view of the parts 45 shown in Fig. 9, the cap being partly broken away.

Referring to the drawings, 15 designates one wall of a barrel. The wall is formed from sheet metal and preferably constitutes one head of the barrel. The wall 15 is pref-

erably provided with a flange 16. 17 indicates an opening formed in the wall 15 and about the opening is disposed an initially raised or distended portion 18. The ring 19 and fastening means therefor are of the type 55 wherein the metal of the barrel wall folds around the flange on the ring and thus forms an annular groove or recess between the folded portions of the metal and the exposed surface of the barrel, which groove receives the free edge of a sealing device, as will later appear. In the construction of ring and fastening means therefor herein shown as one example, the ring 19 comprises an annular body part 19' having at one end a radially extending flange 20 the outer marginal edge portion of which is provided with serrations 21. The inner end of the body portion 19 of the ring is provided with spaced radial notches or recesses 22 of sufficient depth to extend into the plane of the inner face of the barrel head 15, so that when the barrel is inverted, its fluid contents may freely flow through the notches 22 into the ring 19 and outwardly through the bung. 70

From Figure 5 it will be noted that the flange 20 of the bung ring is sealed and mounted in fixed relation to the opening 17 by folding over or overturning the portion 18 about the flange 20 and by crimping the 80 metal of the portion 18 into the serrations 21 of the flange 20. Thus a relatively tight joint and seal are provided between the wall 15, and the ring body 19. The interior of the ring 19 is threaded from end to end to 85 detachably receive therein a threaded plug 23 adapted to be secured into the ring. The construction of the ring flange and method of fastening the ring in position is disclosed in my co-pending application Ser. No. 86,255, 90 filed February 5, 1926. The plug 23 has an outstanding annular shoulder or flange 24 adapted to be turned or screwed down against the rolled over portion of the flange 18. A gasket or packing ring 25 may be interposed 95 between the flange 18 and the shoulder 24. The plug 23 is provided with an outer angularly faced portion providing a nut by means of which the plug may be readily turned. The plug 23 may also have a non-circular 100

recess 26 in its outer end for the reception of a suitable tool shank for interlocking engagement with the plug to turn the same. By forming the plug with the recess 26 the nut portion may be omitted and thus make the 5 plug face flush. The plug 23 may also have upon its inner end an apertured lug 27 to which may be attached a safety device to prevent loss of the plug from the barrel when the plug is released from the ring 19.

10 From Figures 5, 6 and 7 it will be apparent that the portion 18 when folded about the flange 20 provides the annular groove 28 extending entirely around the bung and beneath the serrated flange 20. This groove 28 is utilized for interlocking and sealing a 15 cap 29 to the wall 15 and in operative relation to the plug 23 when the latter is in place. This sealing cap preferably comprises a hollow body part of relatively thin, flexible metal 20 which at its open end is provided with an inwardly extending flange 30. In Figure 6 I have, in dotted lines, shown the cap in its distended form ready for application to the 25 wall 15. As shown, the flange 30 is slightly turned inwardly so that when the cap 29 is forced in a direction toward the wall 15, the flange 30 will bend or flex inwardly and thus slide into the groove 28, and thus become 30 interlocked with the lateral portion 18 of the barrel wall. The cap 29 may be in the form, shown in Figures 6, 7 and 8 wherein the outer end of the cap is provided with an overhanging flange 31, which envelops the shoulder portion 24 of the plug 23 and approaches 35 the nut or central portion of the plug.

In Figures 9 and 10 the outer end of the cap, which is indicated at 32 is closed and completely covers the plug 23, being preferably provided with an outwardly stepped closure wall 33 extending entirely across the outer end of the cap. The cap 32 is in both instances held in place by pressing the cap inwardly against the wall 15 and causing the 45 yieldable flange 30 to move into the groove 28 and effect an interlock with the head.

As the flange 31 overlies the plug, unscrewing partially or entirely of the latter will distort or break the cap and thus the cap will 50 indicate that the plug has been tampered with or removed. On the other hand if the cap 29 is removed as a means of gaining access to the plug 23, it will be so distorted that it cannot be replaced without indicating that 55 it has been tampered with; and likewise, a breaking away of a portion of the cap or distorting it will indicate that the plug 23 has been removed or attempt made to remove it. As a result of the effect incident to 60 tampering with the cap of the plug or both, the cap provides an effective seal or guard for the plug; at the same time due to the flexibility and thinness of the cap it can be readily removed by a person who has authority to remove the plug 23.

It will be noted that the cap 29 fits snugly around the flange 24 and upon the exposed face of the plug, so that slight danger exists of the cap being broken away or distorted in shipment of the barrel or container. 70

It is obvious that various changes and modifications may be made in the details of construction and design of the above specifically described embodiment of this invention without departing from the spirit thereof, 75 such changes and modifications being restricted only by the scope of the following claim.

What I claim is:

In a barrel having a pressed-in bung ring, 80 a sheet metal wall formed with an opening and provided with a pre-formed flange about said opening on one side of said wall, a bung ring arranged to be positioned from the opposite side of said wall and comprising a body portion and an outstanding flange at its outer end having its outer face fitted against said pre-formed flange, whereby the latter provides a seat for a gasket, the metal of the wall adjacent to and surrounding said 85 pre-formed flange being folded around the side edges of said ring flange and inwardly therebelow into concentric relation to said body portion and above the plane of said sheet metal wall, the inner end of said bung ring extending beyond the plane of the inner surface of said wall and formed with notches 90 to a depth substantially co-incident with said plane for permitting complete draining of the 95 barrel. 100

In testimony whereof, I have hereunto subscribed my name.

THEODORE W. RIEKE.
